[57] CLAIM

The ornamental design for a magnetic disk storage case,
as shown and described.

DESCRIPTION

FIG. 1 is a perspective view of a magnetic disk storage
case showing our new design;

FIG. 2 is a left end elevational view of FIG. 1;

FIG. 3 is a rear elevational view of FIG. 1;

FIG. 4 is a bottom plan view thereof;

FIG. 5 is a perspective view of the magnetic disk stor-
age case in the open position and exposed for receipt of
magnetic disks;

FIG. 6 is a left side elevational view of FIG. 5; and

FIG. 7 a cross-sectional view taken along the line 7—7
of FIG. 5.

FIG. 1

FIG. 2

FIG. 3

FIG. 4

FIG. 6
